Primary Examiner — Justin M Jonaitis*Assistant Examiner* — Andrew D Golson(74) *Attorney, Agent, or Firm* — Smart & Biggar LP(57) **CLAIM**

The ornamental design for a door frame as shown and described.

DESCRIPTION

FIG. 1 is a front perspective view of a door frame showing the claimed design;

FIG. 2 is a rear perspective view thereof;

FIG. 3 is a left side view thereof;

FIG. 4 is a front view thereof;

FIG. 5 is a right side view thereof;

FIG. 6 is a rear view thereof;

FIG. 7 is a top view thereof; and,

FIG. 8 is a bottom view thereof.

The door frame includes a symbolic break along its length and width drawn in broken lines. The broken break lines and the area between the break lines forms no part of the claimed design.

1 Claim, 4 Drawing Sheets(56)
